PAPER WINDING MACHINE

William Ernest Stone, Shrewsbury, Mass., assignor to Rice Barton Corporation, Worcester, Mass., a corporation of Massachusetts

Application August 3, 1946, Serial No. 688,258

4 Claims. (Cl. 242—65)

1

This invention relates to paper winding machines and more particularly to that type of paper winding machine known as a "Pope reel" winding machine.

The present type of machine is used principally for winding a web of paper produced by a paper-making machine onto a winding roll. With this type of machine the end portion of a paper web is wound on an empty winding roll which is supported in a position herein called its initial position, in such a manner that the roll engages the under driving drum to the end that the latter element will drive the winding roll. The end portion of the web will begin to wind on said roll and as soon as the web has become firmly fixed to the roll by the winding action, the roll is moved into a secondary position where it remains until the roll has become filled, such movement into this secondary position enabling an empty winding roll to be brought into the primary or initial position.

As soon as the roll which is in the secondary position has become filled, the web is severed and quickly transferred to the new empty winding roll, thus to permit the filled winding roll to be removed without stopping the winding of the paper web.

The present machine utilizes two separate supporting frames which are movable with respect to each other thereby to admit of transference of a roll from one to the other frame, from the initial to secondary or running position.

However, it has been found that the above described mechanism has a serious fault in that the paper web may be either wound too tightly or even sometimes damaged when being wound on a roll supported in the secondary position. This fault is due to the fact that as the paper accumulates on the roll the weight of the roll will increase thus causing the nip-pressure existing between the winding roll and the winder driving drum to become very great. When the nip-pressure becomes too great, the tension in the paper web will become so high as to cause the roll to be wound too tightly or else it will be found that the surface finish of the paper will be damaged.

In the past attempts have been made to overcome these shortcomings in the above described winding mechanism, but none of these prior at-

2

tempts have resulted in a simple and effective answer to the problem. It is, therefore, an object of the present invention to provide a paper winding machine with means whereby the nip-pressure between a winding roll and a driving drum may be adjusted.

It is a further object of the present invention to provide a means whereby the nip-pressure of the present type of machine will be maintained substantially constant as the paper is accumulated upon the winding roll.

With the above and other objects in view as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 represents a top plan view of a reel winding machine.

Fig. 2 is a side elevation of Fig. 1 taken substantially along line 2—2 of Fig. 1 and showing the paper drum in its initial winding position.

Fig. 3 is also taken along line 2—2 of Fig. 1 and shows the paper winding roll in its secondary position.

Fig. 4 is substantially the same as Fig. 3 but illustrating a full paper roll.

Fig. 5 is an enlarged side view, partly in section, of the elements comprising the present invention.

Fig. 6 is a view, partly in section, of the hydraulic cylinder elements taken substantially along line 6—6 of Fig. 1.

Fig. 7 is a top plan view of one of the hydraulic cylinder mounting plates.

Referring particularly to Figs. 1 and 2, the present invention is incorporated in a winding machine which comprises the side frame members 10 and 11 between which is mounted a driving shaft 12 carrying the usual driving drum 13. This driving drum 13 may be driven by a motor 14 or other suitable driving means connected with the shaft 12. Mounted adjacent each end of the driving drum 13 is one of a pair of quadrant arms 15 and 16 each of which is mounted upon a respective shaft 17 and 18 which are in

turn each journaled in a respective one of the side frames 10 and 11. The top portion of each of the quadrant arms 15, 16 is provided with a yoke 19, which is adapted slidably to receive a journal box 20, only one of which is shown. Each journal box 20 has rotatably mounted therein one end of a shaft 21 upon which is mounted the usual paper winding roll 22. As is usual with this type of mechanism, the journal boxes 20 are adapted for vertical movement within the yokes 19, 19 to the end that the paper roll 22 may be readily inserted therein.

The lower end of the quadrant arms 15 and 16 each are provided with a segment gear 23 each of which meshes with a pinion 24 carried by a shaft 25 journaled in the side frame members 10 and 11, the shaft 25 being connected to a hand wheel 26 by means of a gear reduction train located in member 10 all in the usual manner. Thus, an operator by turning the handle 26 may readily swing the quadrant arms 15 and 16 about their axes 17 and 18 thereby to swing the roll 22 about the driving drum 13. Figs. 1 and 2 illustrate the quadrant arms 15 and 16 in their initial positions as resting against stationary stop members 27, 27 which are carried by the frame members 10 and 11.

Also journaled in the opposite frame members 10 and 11 is a shaft 28 upon which are rigidly mounted a pair of arms 29, 29 the tops of which are provided with yokes 30 of a design similar to that of yoke 19. It is the function of the arms 29, 29 to receive the paper roll 22 whenever the quadrant arms 15 and 16 are swung in a counter clockwise direction thus to transfer the journal boxes 20, 20 into the yokes 30, 30.

In the use of the above described mechanism a web of paper 31 is delivered from the driers, calenders, or other parts of a paper making machine, none of which is herein shown, thus, to be wound around the winding roll 22 that is journaled loosely and removably in the upper end of the quadrant arms 15 and 16. The peripheral contact between the driving drum 13 and the winding roll 22 is such as to drive the roll 22 in a clockwise direction thereby to wind the web or paper sheet thereon, the roll 22 being held in engagement with the drum 13 during the winding process by its weight. After a predetermined amount of paper is accumulated on the roll 22, the quadrant arms may be swung in a counter-clockwise direction thereby to transfer the roll 22 from its initial position, as shown in Fig. 2, to a secondary position within the arms 29, 29 as shown in Fig. 3. The roll in this secondary position continues to accumulate paper until a desired amount is reeled thereon. During the time that the paper is being wound upon the roll or reel 22 in this secondary position, the weight thereof increases in proportion to the amount of paper accumulated. In some instances this weight of paper plus the weight imparted by the arms 29, 29 becomes so great that the paper may be damaged or else wound too tightly on the reel 22. As was noted hereinabove, it is the principal object of the present invention to provide means whereby this pressure may be relieved. Referring particularly to Figs. 2 and 5, each of the arms 29, 29 is provided with a bearing sector member 32 which is pivotally secured as at 33 upon the lower portion of the arm 29, and which is adapted to be positioned about the shaft 28 and to be secured to the end of the arm 29 by means of a bolt 34. Depending from this bearing sector 32 is a plate or crank member 35 which

has pivotally secured thereto a piston rod 36 by means of a suitable pin 37. This piston rod 36 extends downwardly to be received within a hydraulic cylinder 38 which snugly embraces a piston head provided on the rod 36. (See Fig. 6.) Each of the cylinders 38, 38 is mounted in a cylinder mounting frame 40 which comprises a base plate 41 secured by means of bolts 42 to a machine base 43. Extending upwardly from the plate 41 are a pair of spaced plates 44 and 45 between which is pivotally mounted the cylinder 38 by means of a pair of cross pins 46 and 47. As may be noted in Figs. 6 and 7, each of the plates 41 is provided with an aperture 48 which permits the lower end of the cylinder 38 to project therethrough. Each of the cylinders 38 has connected to its bottom portion a flexible conduit 49 which in turn is connected to a pipe 50 leading directly to a hydraulic valve box 51. The valve box is connected to a source of fluid under pressure designated generally by the numerals 52 and 52'. A single valve 53 controls the fluid to the end that a single movement of the valve handle 53 may be effective to exert a pressure on each of the piston heads 39 upwardly within the cylinders 38, 38. By moving the valve in the opposite direction the hydraulic pressure is thereby relieved to the end that the piston heads 39, 39 may move freely within the cylinders 38, 38 under the influence of the mechanism connected therewith. Each of the plates 41, 41 is provided with elongated apertures 54 for the purpose of receiving the bolts 42 and by virtue of the elongation of these apertures 54 each of the plates 41 may be adjustably mounted upon the machine base 43 in a manner such that they may be shifted longitudinally of the base 43. Referring to Figs. 5 and 7, the machine base is provided with a pair of angle blocks 55, 55 each of which receives an adjusting bolt 56, the end portion of which is adapted to bear against a respective one of a pair of upright members 57, 57 provided on the plates 41, 41. By loosening the bolts 56, 56 and shifting them in an appropriate manner, each of the plates 41, 41 may be shifted as hereinabove described. Referring to Fig. 3, it is to be noted that when the winding roll 22 is in its secondary position the piston rod 37 is disposed substantially in a vertical line, which line intersects the axis of the shaft 28. Fluid pressure within the cylinders 38, 38, if applied at this time, would be ineffective to alter the pressure existing between the rolls 22 and 13. However, as the paper accumulates upon the roll 22, the center of the roll will move away from the driving drum 13 until a condition exists such as illustrated in Fig. 4. As pointed out hereinabove, the weight of the roll 22 increases proportionately to the amount of paper accumulated thereon and, therefore, the further the center of the roll 22 moves from the drum 13 the heavier the roll 22 becomes. However, when the arms 29, 29 move counterclockwise, as the paper is accumulated on the roll 22, the depending plates or cranks 35, 35 also turn about the axis of shaft 28 to the end that the cylinders 38, 38 are pivoted about their respective axes. Thus, it is to be understood that any hydraulic pressure existing against the piston heads 39, 39 will be effective to produce a turning torque upon the arms 29, 29 in a counterclockwise direction, thereby to relieve the pressure between the roll 22 and the drum 13. It is to be understood, that the further the arms 29, 29 turn about the axis of shaft 28 the greater will be the mechanical advantages of the pistons

36, 36. Therefore, the greater the weight of the roll 22 the greater will be the effective pressure that the pistons 36, 36 can bring to bear upon the arms 29, 29. The present invention contemplates the use of a constant pressure within the cylinders 38, 38 throughout the entire winding cycle. Whenever the valve 51 is opened, a constant head or pressure of fluid will be exerted upon the piston heads 39, 39 and this pressure may be so selected that the so-called nip-pressure existing between the roll 22 and the driving drum 13 may be substantially constant throughout the entire winding operation. In other words, as soon as the roll 22 is transferred from the quadrant arms 15 and 16 to the arms 29, 29 the valve 51 may be opened thus permitting the hydraulic pressure to be exerted against the piston heads 39, 39. However, in the position shown in Fig. 3, this pressure will not be effective to add or detract from the normal pressure existing between the rolls 22 and 13 due to the fact that the pistons 36, 36 are in this position disposed directly in line with the shaft axis 28. As the arms 29, 29 swing outwardly, the constant pressure exerted upon the piston heads 39, 39 will become increasingly effective to force the arms 29, 29 away from the drum 13 to the end that the increased weight of the roll 22 will be proportionately compensated for.

The present invention also contemplates that the pistons 36, 36 may be used to increase the nip-pressure existing between the roll 22 and the drum 13 at their initial winding stages. In order to increase this nip-pressure the mounting plates 41, 41 may be moved out to the right-hand end of the frame members 10 and 11 thereby to produce a clockwise turning torque upon the arms 29, 29. However, as the arms 29, 29 swing in a counterclockwise direction, this positive addition of pressure upon the roll 22 and the drum 13 will be entirely eliminated and upon further movement of the arms 29, 29 the pistons 36, 36 will be effective to produce a counterclockwise torque upon the arms 29, 29 as hereinabove described. The bearing plates 41, 41 are only adjusted in this manner in the event that the normal weight of the roll 22 and the arms 29, 29 is not sufficient to produce a proper amount of nip-pressure between the roll 22 and the drum 13.

From the above it is to be understood that each of the plate or crank members 35 functions as a force-compounding means which, when rotated in a counterclockwise direction, is effective to multiply the constant piston force to the end that the arms 29, 29 are biased away from the drum 13 with a force substantially proportional to the angular distance moved by said arms. Each of the cranks 35 forms in conjunction with its respective piston 36, a toggle mechanism which, when it is in its straight-line position as shown in Fig. 5 is ineffective to bias the arms 29, 29 in any direction as the resultant force of the piston passes directly through the pivotal axes of the arms 29, 29.

Therefore, from the above description it is to be understood that the present invention provides a means whereby the nip-pressure may be maintained substantially constant throughout the entire winding operation. Thus, by selecting a proper hydraulic fluid pressure and by selecting a proper position for the cylinder pivots, the paper may be wound upon the winding roll without being damaged or being wound too tightly.

I claim:

1. In a paper winding machine having a driving

drum, a pair of arms pivotally supported adjacent said driving drum, a paper winding roll carried by said arms and disposed in surface contact with said driving drum for being driven thereby and for winding paper upon said winding roll, toggle means having one link thereof connected to and movable in unison with and about the axis of said arms while its other link is pivotally connected to a normally stationary means, and means to apply a force against said toggle means at all times, said toggle means and said last mentioned means being so positioned that when said winding roll is empty the resultant of said force passes directly through and at right angles to the pivotal axis of said arms, and said toggle means being adapted, in response to an angular movement of said arms, to bias said arms away from said driving drum with a force substantially proportional to the angular distance moved by said arms.

2. In a paper winding machine having a driving drum, a pair of arms pivotally supported adjacent said driving drum, a paper winding roll carried by said arms and disposed in surface contact with said driving drum so as to be driven thereby; the improvement which consists in the provision of means for controlling automatically the pressure between the driving drum and said winding roll, said means comprising, a hydraulically actuated piston for biasing said winding roll away from said driving drum, and crank means connecting said arms with said piston in the manner of a toggle mechanism so that said piston is ineffective to bias said winding roll away from said driving drum when said winding roll is in a predetermined position and so that said piston is effective, in response to an angular movement of said arms, to bias said arms away from said driving drum with a force substantially proportional to the angular distance moved by said arms.

3. In a paper winding machine having a driving drum, a pair of arms pivotally supported adjacent said driving drum, a paper winding roll carried by said arms and disposed in surface contact with said driving drum so as to be driven thereby; the improvement which consists in the provision of means for controlling automatically the pressure between the driving drum and said winding roll, said means comprising, a piston pivotally supported about an axis disposed in parallelism with the pivotal axis of said arms and at right angles to the path of piston movement, a crank pivotally connected with said piston and rigidly connected with said arms, and means to bias said piston toward said crank, said crank and said piston forming a toggle mechanism effective to bias said winding roll either toward or away from said driving drum depending upon the position of said arms relative to said driving drum, and said toggle mechanism being ineffective to bias said arms in either direction when said toggle mechanism is in a straight line position.

4. In a paper winding machine having a driving drum, a pair of arms pivotally supported adjacent said driving drum, a paper winding roll carried by said arms and disposed in surface contact with said driving drum so as to be driven thereby; the improvement which consists in the provision of means for controlling automatically the pressure between the driving drum and said winding roll, said means comprising, a piston pivotally supported about an axis disposed in parallelism with the pivotal axis of said arms

and at right angles to the path of piston movement, a crank pivotally connected with said piston and rigidly connected with said arms, and means to bias said piston toward said crank, said crank and said piston forming a toggle mechanism, said toggle mechanism being so positioned that when said winding roll is empty the resultant force exerted by said biasing means passes directly through and at right angles to the pivotal axis of said arms, and said toggle mechanism being adapted, in response to an angular movement of said arms, to bias said arms away from said driving drum with a force substantially proportional to the angular distance moved by said arms. 10
